UNITED STATES PATENT OFFICE.

JUSTUS HATTEMER, OF WEST NEW YORK, NEW JERSEY, ASSIGNOR TO HARDMAN, PECK & COMPANY, OF NEW YORK, N. Y., A CORPORATION OF NEW YORK.

BRAKE FOR SELF-PLAYING MUSICAL INSTRUMENTS.

No. 847,770.

Specification of Letters Patent.

Patented March 19, 1907.

Application filed November 6, 1906. Serial No. 342,277.

To all whom it may concern:

Be it known that I, JUSTUS HATTEMER, a citizen of the United States, residing at West New York, in the county of Hudson and State of New Jersey, have invented certain new and useful Improvements in Brakes for Self-Playing Musical Instruments; and I do hereby declare the following to be full, clear, and exact description of the invention, such as will enable others skilled in the art to which it appertains to make and use the same.

This invention relates to self-playing musical instruments, and especially to keyboard playing instruments operating with a perforated music-sheet.

An object of the invention is to provide in a self-playing musical instrument a take-up spool having an improved brake mechanism associated therewith to prevent the take-up spool from "racing" during the rewind.

A further object of the invention is to provide in a device of the class a brake-disk applied to the shaft of a take-up spool and with a spring-pressed brake-shoe arranged to bear yieldingly upon the brake-disk with means operated from the rewind mechanism for releasing the tension of the brake during the winding.

With these and other objects in view the invention comprises certain other novel constructions, combinations, and arrangements of parts, as will be hereinafter more fully described and claimed.

In the drawings, Figure 1 is a view of the improved brake mechanism shown in side elevation and associated with a fragment of a conventional take-up spool. Fig. 2 is a view of the brake mechanism shown in end elevation.

Like characters of reference designate corresponding parts throughout the several views.

The improved brake mechanism forming the subject-matter of this application is adapted for association with a keyboard self-playing instrument or attachment for playing keyboard instruments wherein a take-up spool 10 is provided with a trunnion 11, journaled in a cheek-plate 12. The trunnion 11 preferably extends outwardly through the cheek-plate and is provided with an axially-extending shaft 13. To the side

of the cheek-plate is rigidly secured a bracket 14, bent outwardly and then upwardly to accommodate and journal the extremity of the shaft 13. Upon the bracket 14 is rigidly secured another bracket 15, provided with a pointed screw 16, engaging the end of the shaft 13, and with a knurled head 17 for adjusting the screw 16 and a knurled jam-nut 18 for securing the screw at an adjusted position. Between the upwardly-extending end of the bracket 14 and the cheek-plate 12 is defined a space within which a brake-disk 19 is rigidly secured to the shaft 13 in any approved manner, as by means of a set-screw 20 inserted through the hub 21 and engaging the shaft 13 in the usual well-known manner.

At any convenient place a block 22 is rigidly secured to the cheek-plate 12, and thereupon is secured a spring or resilient member 23, curved to extend upwardly partially about the brace 19 and provided at its upper end with a brake-shoe 24. The brake-shoe 24 is provided with a concavity 25 of less radius than the arc of the disk 19, so that the brake-shoe 24 bears upon the disk 19 only at the extremities of the concavity. The spring 23 is secured to the block 22 in any approved manner, as by a screw 26, and a second screw, as 27, is provided bearing against the spring 23 and above a recess 28, formed in the block 22, by means of which the tension of the spring 23 is adjusted.

For releasing the brake-shoe 24 from contact with the disk 19 during the operation of winding the music-sheet a shaft 29 is journaled, as in the blocks 30 and 31, and at its upper end is provided with a substantially right-angularly-disposed offset portion 32, engaging the inner side of the brake-shoe 25 and preferably within a notch 33, formed therein. At its lower end the shaft 29 is provided with a similar right-angularly-disposed offset 34, disposed in a plane at right angles to the plane of the offset 32, and its extremity is connected with the rewind apparatus, as at 35, whereby the shaft 29 is turned upon its axis to force the shoe 24 outwardly while the instrument is playing and while the music-sheet is being wound upon the take-up spool 10, so that no friction is produced by the shoe 24 upon the disk 19 except during rewind, and then to prevent the spool 10 from racing.

It will be readily understood that while the

instrument is playing the shaft 29 is so turned that the offset portion 32 forces the brake-shoe 24 out of contact with the periphery of the disk 19, so that the take-up spool 10 may be rotated by the usual and ordinary mechanism (usually applied at the other end) for winding the music-sheet. As soon as the music-sheet has been entirely rewound the rewind mechanism is thrown into operation in the usual well-known manner, and by means of the connection 35 the shaft 29 is released and the brake-shoe 24 thrown into yielding engagement with the disk 19 by means of the spring 23.

15 What I claim is—

1. In a mechanism of the class described, a cheek-plate, a take-up spool provided with a trunnion extending through the cheek-plate, a bracket secured to the cheek-plate and forming a bearing for the trunnion, an auxiliary bracket secured to the bracket, and a pointed screw extending through the auxiliary bracket, and engaging the axial extremity of the trunnion.

2. In a mechanism of the class described, a cheek-plate, a take-up spool having a trunnion extending through the cheek-plate, a bracket secured to the cheek-plate and forming a bearing for the trunnion, an auxiliary bracket secured to the bracket, a pointed screw inserted through the auxiliary bracket and engaging the axial extremity of the trunnion, a friction-disk disposed upon the trunnion, and a brake yieldingly engaging the 35 friction-disk.

3. In a mechanism of the class described, a cheek-plate, a take-up spool provided with a trunnion extending through the cheek-plate, a bracket rigidly secured to the cheek-plate and embodying a bearing for the trunnion, an auxiliary bracket secured to the bracket, a pointed screw inserted through the auxiliary bracket, and engaging the axial extremity of the trunnion, a friction-disk carried by the trunnion between the bracket and the cheek-plate, a friction-shoe yieldingly engaging the friction-disk, and means to disengage the friction-shoe from the disk.

4. In a mechanism of the class described, a cheek-plate, a take-up spool provided with a trunnion extending through the cheek-plate, a bracket secured upon the cheek-plate, providing a journal-bearing for the trunnion, a friction-disk carried rigidly upon the trunnion within the bracket, a block secured to the cheek-plate, a spring secured to the block, a brake-shoe carried by the spring in yielding engagement with the periphery of the friction-disk, a shaft extending along and journaled upon the surface of the cheek-plate, and provided with an offset in engagement with the brake-shoe, and means to move the shaft angularly.

In testimony whereof I affix my signature in presence of two witnesses.

JUSTUS HATTEMER.
